DESIGN FOR A TOY PISTOL

Myron Fleishman, Bronx, N. Y.

Application June 6, 1947, Serial No. 139,481

Term of patent 7 years

(Cl. D34—15)

To all whom it may concern:

Be it known that I, Myron Fleishman, a citizen of the United States, residing in the Bronx, county of Bronx, and State of New York, have invented a new, original, and ornamental Design for a Toy Pistol, of which the following is a specification, reference being had to the accompanying drawing, forming part thereof:

Fig. 1 is a top plan view of a toy pistol, showing my new design;

Fig. 2 is a side elevational view thereof; and

Fig. 3 is a front elevational view thereof.

The opposite side of the device appears sub-

stantially the same as the side thereof shown in Fig. 2.

I claim:

The ornamental design for a toy pistol, substantially as shown and described.

MYRON FLEISHMAN.
